UNITED STATES PATENT OFFICE.

JOSEPH WHITE, OF MIDDLESEX, NEW JERSEY; MINNIE E. WHITE, ADMINISTRATRIX OF SAID JOSEPH WHITE, DECEASED, ASSIGNOR, BY MESNE ASSIGNMENTS, TO R. HOE AND CO., OF NEW YORK, N. Y., A CORPORATION OF NEW YORK.

PRINTING DEVICE.

Application filed December 24, 1920, Serial No. 432,933. Renewed July 2, 1924.

To all whom it may concern:

Be it known that I, JOSEPH WHITE, a citizen of the United States, residing at Middlesex, in the county of Middlesex and State of New Jersey, have invented certain new and useful Improvements in Printing Devices, of which the following is a specification.

My present invention relates to printing devices useful particularly where the printing is from forms made up of a plurality of electrotype plates, as is usual.

One of the objects of my invention is to provide a form-bed on which the several plates may be adjusted in correct printing relation to each other, and then non-adjustably attached to the bed by means which will obviate the present difficulty which arises with the usual form of hooks which engage the vertical or beveled edges on each plate. Such hooks frequently become embedded in the edge of the plate by the printing pressure so that the plate shifts from its correct printing position.

Another object of my invention is to provide means by which the plate may be moved into correct position on such a bed and held there temporarily while the fastening devices are being inserted.

Another object of my invention is to provide devices by which the several plates with the form may be adjusted in appropriate relation to each other, according to a key sheet, and after the plates are appropriately positioned, they may be attached to the bed.

Another object of my invention is to provide devices by which a form may be made up, and preferably a make-ready for such a form also be prepared on an impression cylinder, and then the prepared form and prepared impression surface may be removed from the machine on which they were originally adjusted and attached to a printing press.

Another object of my invention is to provide a removable bed and a removable impression surface for a cylindrical printing couple, the active surfaces of which extend more than 180 degrees around the cylinders.

With these and other objects in view, my invention consists in the methods and apparatus hereinafter described and more spe-

cifically pointed out in the appended claims.

In the drawings, Figure 1 is a side elevation, partly in section, of a printing press on which some features of my invention are shown and which may be used to carry out my novel methods; Fig. 2 is a fragmentary enlarged section through the form cylinder of Fig. 1; Fig. 3 is a plan view of a form-bed embodying my invention; Fig. 4 is a plan view, and Fig. 5 a sectional elevation of one portion of my illustrative form of locking devices, together with my illustrative form of plate positioning and clamping device; and Fig. 6 is a section on the line 6—6 of Fig. 4 looking in the direction of the arrow.

Corresponding parts have corresponding reference characters in the several views.

The form of bed which I have adopted for purposes of illustration is shown at 10 as comprising a plate supporting member having a smooth plate supporting surface 75 and a ribbed interior formed of the intersecting ribs 11. Extending through the plate supporting surface are a plurality of holes 12, which preferably will be placed in the bed in some regular pattern between the 80 ribs.

The bed 10, in the illustrative form, is supported on the form cylinder 13 which is constructed so that a drilling tool may be passed through holes 14 in the bed supporting surface of the cylinder, the holes 14 being in alignment with the holes 12.

Preferably, the plates will be fastened to the bed by means of headed screws 15, the bodies of which extend through the holes 12 and the ends of which are tapped into the soft metal backing of the plate P. In inserting the plate fasteners, the plate P is first moved to its desired position and preferably is then temporarily clamped in said position. Then the drill is passed through one of the holes 14 and the corresponding hole 12, and a small hole drilled in the soft metal backing. Then the screw 15 is passed through the two holes and by means of a suitable tool is forced into the soft metal backing, so that the threads on the screw will cut corresponding threads in the backing.

In order to accommodate any of the soft metal which may be forced out of the tapped hole by the insertion of the screw

15, I preferably provide a clearance space 16 around each of the holes 12.

It will be understood that a plate held in this manner will be securely attached to the 5 bed and will be better adapted to resist the motion along the bed which may be induced by the printing pressure than would be the case if the plate were held by hooks engaging with the beveled edges, as is usual.

10 In making up a form comprising a plurality of separate plates, great difficulty is found in locating the plates in the appropriate relation on the printing bed. To overcome this difficulty, I have provided the 15 devices, such as are illustrated in Fig. 1, by which the key sheet may be attached to what is the equivalent of an impression surface, and a locating device may then be moved over the key sheet and the printing bed, so that a position on the bed corresponding to a selected position on the key sheet may be accurately indicated, so that the corresponding printing plate may be attached to the 20 bed in appropriate position.

25 In the illustrative form, I have provided a printing couple comprising a form cylinder 13 and an impression cylinder 17 mounted in the usual manner to rotate in bearings 18 and 19, the latter bearing being made eccentric and provided with means by which the printing couple may be thrown into and out of impression, all in the usual manner. The printing couple may be rotated by a 30 motor 20 driving a pulley 21 on a shaft 22 having a gear 23 engaging with a gear on the form cylinder 13. A feed board 24 may be provided, together with sheet gages 25. There may also be provided the usual delivery rings or cylinder 26 and the fly 27. 35 Suitable inking rollers 27' are also provided. The parts so far described constitute the usual portions of a printing press, and further description thereof will be unnecessary.

40 The form-bed 10 is a cylindrical shell detachably connected to the surface 14 of the cylinder 13 by the bolts 28 and, in the form illustrated, this bed extends more than 180 degrees around the cylinder 13. Since such a bed preferably is to be removed from the cylinder 13, it is necessary to construct the cylinder 13 so that this may be accomplished. To this end, I make the gap between the ends of the segment 14 of such a 45 size that there will be a diameter across the cylinder 13 which will be smaller than the shortest distance between the ends of the form-bed 10. If the ends of the segment 14 are connected by solid portions, as is usual, such solid portions 29 will be formed so as not to interfere with the removal or replacement of the bed 10. In the construction illustrated, it will be seen that by removing the bolts 28 and turning the bed 10 50 on the cylinder 13 until the ends of the bed

10 are opposite the shortest diameter across the cylinder, the bed 10 may then be removed from the cylinder, although its surface extends more than half way around such cylinder.

70 Similarly, the impression surface on the cylinder 17 is preferably formed of a removable cylindrical shell 30, removably attached thereto by bolts 31 and preferably provided with a clamp bar 32 at the front 75 and a reel rod 33 at the rear, the clamp bar and the reel rod being connected to the surface member 30 independently of the cylinder. The cylinder 17 has the usual sheet grippers 34 which will be operated in the 80 usual manner to take a sheet from the guides 25 and carry it past the impression point to the delivery rings 26.

85 On the rod 35 extending across the machine is slidably mounted the locating devices which, in the form illustrated, comprise a double armed member 37 on opposite ends of which are pivotally mounted arms 38, 39, each carrying at their outer ends transparent plates 40 and 41, respectively, having cross lines 42 thereon. The relative positions of the two arms of the member 37 may be adjusted by the stud 73 and the nut 74, which serve to clamp the two arms 70, 71 in adjusted position. Adjusting screws 43 are provided to regulate the height of the plates 40 and 41. The cross lines on the plates 40 and 41 are situated so that the angular distance from the impression point to such cross lines is the same for each, but on opposite sides of the vertical plane passing through the line of impression. Consequently, a point under one set of cross lines will reach the impression line at precisely the same time when the corresponding point under the other cross line reaches the impression line as the printing couple is rotated.

100 A make-ready sheet is fastened on its flat end under the clamp bar 32 and is stretched around the surface 30 by the reel rod 33. The key sheet is then attached to the cylinder 17 preferably by feeding out to the gages 25 so that it will be taken by the grippers 34, the key sheet being smoothed on the surface by the brush 50, if desired, by one or more rotations of the printing couple while the cylinders are out of engagement. The couple is then stopped with the first portion of the key sheet beneath the plate 115 41. The printing plate corresponding to this point is then placed on the bed 10 beneath the plate 40 and is moved until the corresponding point on the printing plate is beneath the cross lines on the plate 40. 120 This will locate the printing plate in correct position in relation to the key sheet. In order to give a slow, fine motion to the adjustment of the printing plate, I provide 125 pushing fingers 51 controlled by adjusting 130

screws 52 and handles 53, these pushing fingers engaging the edges of the plate so that it may be moved slowly and with precision until the desired point is located beneath the cross lines 32. The fingers 51 may be adjustably mounted in the holders 54 on the ends of the screws 52 so as to accommodate different sizes of printing plates.

The pushing fingers and their devices are carried in a frame 55 slidably mounted on rods 56, 56 extending across the machine. On rods 57, 57 also carried by the frame 55 are temporary clamping devices which, in the form illustrated, comprise a vertically movable clamping member 58 having a soft rubber end 59 and a clamping screw 60, the latter passing through a lug 61 on the rod 57.

By the devices just described, the printing plate may be first brought accurately into position beneath the cross lines 42 and then the clamping members 58 are brought down to hold the plate in position. If the form of fastening devices, illustrated in Figs. 2 and 3, is used, the plate is held in this position until such fasteners are inserted. In some forms of my invention, it may be desired to use edge hooks, and in such case, such edge hooks are brought into engagement with the printing table and fastened in position. By the rotation of the printing couple to bring new portions of the impression surface and the bed into position beneath the locating devices and by moving the latter longitudinally of the cylinders, the form may be made up, one plate at a time until the entire form is assembled with each of the plates thereof located in exact position in relation to the other plates, in accordance with the key sheet.

If desired, the locating device may now be moved to one side and the make-ready sheet may be prepared. This will be done in the usual manner by building up on the make-ready sheet until the desired printing effects are obtained.

If desired, the printing of sheets on the form and make-ready sheets as thus prepared may be done on the same machine on which they were originally prepared. Where, however, there are a number of presses or where the change of form is sufficiently frequent, it may be desired to provide a series of printing presses to which the prepared forms and make-ready sheets may be transferred from the machine of Fig. 1. Such machines will be the duplicate, so far as the printing couple is concerned, of Fig. 1, so that the form-bed 10 and the impression surface 30 may be removed from the cylinders 13 and 17, respectively, without disturbing any of the parts carried thereby and attached to the printing press proper, on which printing may be be-

gun at once without any delay as would be caused by preparing the form and the make-ready on such a press.

While I have described my invention as applied to a cylindrical printing couple, it will be understood that it may also be applied to a flat bed construction. It will furthermore be understood that while preferably the several features of my invention are used together, many of them are capable of use alone or in combination with only some of the remaining features. For instance, my form-bed and the method of attaching the plates thereto may be used in connection with any kind of printing press either flat bed or cylinder and without the use of my locating devices. It will also be understood that my removable surface carrying the make-ready sheet connected thereto may be used independently of my illustrative form of form-bed.

It will also be understood that the arrangement which I have described is merely illustrative, and that the embodiments thereof may be varied within wide limits.

I claim:

1. The method of locating the individual plates of a printing form in desired relation on a printing bed, which consists in sliding each plate over the bed to desired position, clamping the plate temporarily in position and then fastening the plate non-adjustably to the bed.

2. The method of locating the individual plates of a printing form in the same relation on a printing bed as the corresponding impressions occupy on a key sheet, which consists in moving each plate to the same relative position as the impression of said plate occupies on the key sheet and then fastening the plate non-adjustably to the bed.

3. The method of locating the individual plates of a printing form in the same relation on a printing bed as the corresponding impressions occupy on a key sheet, which consists in moving each plate to the same relative position as the impression of said plate occupies on the key sheet, clamping the plate temporarily in position, and then fastening the plate non-adjustably to the bed.

4. The method of locating the individual plates of a printing form in desired relation on a printing bed, which consists in moving each plate individually to desired position, drilling a hole in the soft metal backing of the plate through a hole in the bed, passing the body of a headed screw through the hole in the bed and screwing its threaded end into the soft metal backing to fasten the plate in position on the bed.

5. The method of locating the individual plates of a printing form in desired relation on a printing bed, which consists in moving each plate to desired position, clamping the

plate temporarily in position and then drilling a hole in the soft metal backing of the plate through a hole in the bed, passing the body of a headed screw through the hole in the bed and screwing its threaded end into the soft metal backing to fasten the plate in position on the bed.

6. A printing form comprising a printing bed, a plurality of printing plates mounted thereon, and fastening members for the plates comprising headed screws extending through the bed and screwed into small holes formed in the soft metal backing of the plate, the plate supporting surface of the bed having recesses surrounding the screws and adapted to receive the soft metal of the plate forced therefrom when the screws are forced into the small holes in the plate.

20. 7. A device for locating the plates of a printing form on a bed, comprising means for sliding the plate over the bed to desired position, means to clamp the plate to the bed temporarily after it is in position, and means to fasten the plate non-adjustably to the bed.

8. A device for locating the plates of a printing form on a bed, comprising means for sliding the plate over the bed to desired position, means to clamp the plate to the bed temporarily after it is in position, and headed screws extending through the bed and screwed into the body of the plate to fasten the plate to the bed.

30. 9. A printing element, comprising a cylinder having a cylindrical bed supporting segment extending more than 180 degrees around the cylinder with a gap between the ends of the segment, and a cylindrical segmental form-bed detachably connected to the cylinder and having a form supporting surface of more than 180 degrees in circumference.

45. 10. A printing element, comprising a cylinder having a cylindrical bed supporting segment extending more than 180 degrees around the cylinder, and a depressed segment connecting the ends of said segment, and a cylindrical segmental form-bed detachably connected to the cylinder and having a form supporting surface of more than 180 degrees in circumference, the shortest distance between the ends of said form-bed being greater than the greatest distance 50 across said bed supporting segment and said depressed segment.

60. 11. A printing bed and a key sheet support adapted to be positioned in fixed relation to each other, means to attach the key sheet to its support, and means whereby a printing plate may be located on the bed in a position in relation to the other plates of the form corresponding to the position which the impression of that plate bears to the key sheet, said means comprising a member having a pair of locating devices in fixed relation to each other, said member being mounted so that one indicating device may be brought into position over any selected point on the key sheet, whereby the other indicating device will indicate the position on the bed of the point on the plate corresponding to the selected point on the key sheet.

65. the impressions of the other plates on the key sheet.

12. A printing bed and a key sheet support adapted to be positioned in fixed relation to each other, means to attach the key sheet to its support, and means whereby a printing plate may be located on the bed in a position in relation to the other plates of the form corresponding to the position which the impression of that plate bears to the impressions of the other plates on the key sheet, said means comprising a member having a pair of locating devices in fixed relation to each other, said members being mounted so that one indicating device may be brought into position over any selected point on the key sheet, whereby the other indicating device will indicate the position on the bed of the point on the plate corresponding to the selected point on the key sheet.

85. 13. A printing bed and a key sheet support adapted to be positioned in fixed relation to each other, means to attach the key sheet to its support, and means whereby a printing plate may be located on the bed in a position in relation to the other plates of the form corresponding to the position which the impression of that plate bears to the impressions of the other plates on the key sheet, said means comprising a member having a pair of locating devices in fixed relation to each other, said member being mounted so that one indicating device may be brought into position over any selected point on the key sheet with the other device over the bed, and means to move a plate over the bed to bring beneath the other device a point on the plate corresponding to the selected point on the key sheet.

95. 14. A printing bed and a key sheet support adapted to be positioned in fixed relation to each other, means to attach the key sheet to its support, means whereby a printing plate may be located on the bed in a position in relation to the other plates of the form corresponding to the position which the impression of that plate bears to the impressions of the other plates on the key sheet, said means comprising a member having a pair of locating devices in fixed relation to each other, said member being mounted so that one indicating device may be brought into position over any selected point on the key sheet with the other device over the bed, and means to move a plate over the bed to bring beneath the other device a point on the plate corresponding to the selected point on the key sheet.

105. 15. A pair of cylinders having parallel axes and geared to rotate in unison, one of said cylinders being adapted to support a key sheet attached thereto, and the other

cylinder having a printing plate bed, a member mounted for movement longitudinally of the axes of the cylinders and having a pair of locating devices in fixed relation to each other, with each device extending over and adjacent to the periphery of one of the cylinders.

16. A printing couple comprising a pair of cylinders of the same printing diameter, 10 one of said cylinders being adapted to support a key sheet attached thereto, and the other cylinder having a printing plate bed adapted to support the form, a member mounted for movement longitudinally of the 15 axes of the cylinders and having a pair of locating devices in fixed relation to each other with each device extending over and adjacent to the periphery of one of the cylinders, with the points under the indicating devices having the same angular relation 20 with the line of contact of the cylinders.

17. A pair of cylinders having parallel axes and geared to rotate in unison, one of said cylinders being adapted to support a 25 key sheet attached thereto, and the other cylinder having a printing plate bed, a member mounted for movement longitudinally of the axes of the cylinders and having a pair of locating devices in fixed relation to each other, with each device 30 extending over and adjacent to the periphery of one of the cylinders, and means over the cylinder having the bed to move a printing plate on the bed into position beneath 35 the locating device over that cylinder.

18. A pair of cylinders having parallel axes and geared to rotate in unison, one of said cylinders being adapted to support a key sheet attached thereto, and the other 40 cylinder having a printing plate bed, a member mounted for movement longitudinally of the axes of the cylinders and having a pair of locating devices in fixed relation to each other, with each device 45 extending over and adjacent to the periphery of one of the cylinders, and means over the cylinder having the bed to move a printing plate on the bed into position beneath the locating device over that cylinder, said bed and its cylinder being arranged to permit plate fastening devices to 50 be passed through the bed from the underside thereof into the body of the plate.

19. A pair of cylinders having parallel 55 axes and geared to rotate in unison, one of said cylinders being adapted to support a key sheet attached thereto, and the other cylinder having a printing plate bed, a member mounted 60 for movement longitudinally of the axes of the cylinders and having a pair of locating devices in fixed relation to each other, with each device extending over and adjacent to the periphery of one of the cylinders, means 65 over the cylinder having the bed to move a

printing plate on the bed into position beneath the locating device over that cylinder, and means to clamp the plate temporarily to the bed when positioned, said bed and its cylinder having openings arranged to permit 70 plate fastening devices to be passed through the bed from the underside thereof into the body of the plate.

20. A cylinder having a printing plate bed removably attached to the periphery thereof, said bed having a smooth outer surface and a plurality of smooth-walled openings extending through the member, and the cylinder having a plurality of openings 75 through its walls in alignment with the openings in the bed, whereby plate fastening devices may be passed through the cylinder and the bed into the body of the printing plates.

21. A cylinder having a printing plate 80 bed removably attached to the periphery thereof, said bed having a smooth outer surface and a ribbed bottom surface and a plurality of smooth-walled openings extending through the member between the ribs, 85 and the cylinder having a plurality of openings through its walls in alignment with the openings in the bed, whereby plate fastening devices may be passed through the cylinder and the bed into the body of the printing 90 plates.

22. In a printing press, a printing couple comprising a pair of cylinders each having a cylindrical bed removably attached thereto, means to attach a make-ready sheet to 100 the impression bed, means to attach a key sheet temporarily to the impression bed, means whereby each of a plurality of printing plates may be located on the form-bed in a position on that bed corresponding to the 105 position of the impression of that plate on the key sheet, and means to attach the plates to the form-bed after they have been positioned.

23. In a printing press, a printing couple 110 comprising a pair of cylinders each having a cylindrical bed removably attached thereto, means to attach a make-ready sheet to the impression bed, means to attach a key sheet temporarily to the impression bed, 115 means whereby each of a plurality of printing plates may be located on the form-bed in a position on that bed corresponding to the position of the impression of that plate on the key sheet, and means to attach the 120 plates to the form-bed after they have been positioned by fastening members extending through the bed from the underside thereof into the body of the plate.

24. In a printing press, a printing couple 125 comprising a pair of cylinders each having a cylindrical bed removably attached thereto, means to attach a make-ready sheet to the impression bed, means to attach a key sheet temporarily to the impression bed, 130

means whereby each of a plurality of printing plates may be located on the form-bed in a position on that bed corresponding to the position of the impression of that plate 5 on the key sheet, said means comprising a member movable longitudinally of the axes of the cylinders and having a pair of locating devices in fixed relation to each other and each extending over one of the beds, 10 and means to attach the plates to the form-bed after they have been positioned.

25. In a printing press, a printing couple comprising a pair of cylinders each having a cylindrical bed removably attached thereto, 15 to, means to attach a make-ready sheet to the impression bed, means to attach a key sheet temporarily to the impression bed, means whereby each of a plurality of printing plates may be located on the form-bed 20 in a position on that bed corresponding to the position of the impression of that plate on the key sheet, said means comprising a member movable longitudinally of the axes of the cylinders and having a pair of locating 25 devices in fixed relation to each other and each extending over one of the beds,

and means to fasten the plates to the form-bed after they have been positioned by fastening members extending through the bed from the underside thereof into the body of 30 the plate.

26. In a printing press, a printing couple comprising a pair of cylinders each having a cylindrical bed removably attached thereto, 35 means to attach a make-ready sheet to the impression bed, means to attach a key sheet temporarily to the impression bed, means whereby each of a plurality of printing plates may be located on the form-bed in a position on that bed corresponding to the 40 position of the impression of that plate on the key sheet, and means to attach the plates to the form-bed after they have been positioned, said beds each extending more than 45 180 degrees around the cylinder which supports it and said cylinders, and said beds being constructed and arranged to permit the removal of the beds from the cylinders in a direction at right-angles to the axes of the cylinders. 50

JOSEPH WHITE.
